WHEEL COVER

Henry G. Haga, Royal Oak, and Bernard N. Smith, Oak Park, Mich., assignors to General Motors Corporation, Detroit, Mich., a corporation of Delaware

Filed Feb. 6, 1961, Ser. No. 63,847

Term of patent 7 years

(Cl. D14—30)

In the drawings:

We claim:

The ornamental design for a wheel cover, substantially as shown.
